(57) **CLAIM**

The ornamental design for a magnetic identification label, as shown and described.

DESCRIPTION

FIG. 1 is a front perspective view of the design of a magnetic identification label, showing a new design;

FIG. 2 is a top plan view thereof;

FIG. 3 left side elevation view thereof;

FIG. 4 is an end elevation view thereof; and,

FIG. 5 is a front perspective view of the magnetic identification label shown in an environment of use.

The broken line portion of the figure drawings is included to show environment that forms no part of the claimed design.

1 Claim, 3 Drawing Sheets
